(Cl. D9—2)

To all whom it may concern:

Be it known that I, John J. Cinelli, a citizen of the United States, residing at Chicago, in the county of Cook and State of Illinois, have invented a new, original, and ornamental Design for a Combined Motor, Blower, and Cover for a Vacuum Cleaner Housing, of which the following is a specification, reference being had to the accompanying drawing, forming part thereof.

Fig. 1 is a side elevational view showing my new design for a combined motor, blower, and cover for a vacuum cleaner housing; and

Fig. 2 is a top plan view of same.

I claim:

The ornamental design for a combined motor, blower, and cover for a vacuum cleaner housing, substantially as shown.

JOHN J. CINELLI.
